UNITED STATES PATENT OFFICE

FREDERICK W. LAENCHER, OF ELMHURST, NEW YORK, ASSIGNOR TO A. KIMBALL COMPANY, OF NEW YORK, N. Y., A CORPORATION OF NEW YORK

TAG

Application filed November 17, 1928. Serial No. 320,075.

This invention relates to price tags of the variety known as pin tickets, this name being commonly applied to that class of tags which are provided with wire staples which are adapted to penetrate the goods to which they are to be attached, after which the ends of the staples are bent over to prevent accidental removal.

It is an object of the present invention to provide a pin ticket and a method of making the same in which the ends of the staples which penetrate the goods are so formed as to present a substantially smooth, rounded end, whereby the danger of injuring the goods or the hands of the users because of contact with jagged edges of the ends of ordinary staples is substantially eliminated.

It is an additional object of the invention to provide a pin ticket in which only non-corrodible material is exposed at the ends of the staples, thus additionally protecting the goods against damage from rust stains, etc.

Other objects and advantages of the invention will appear hereinafter.

A preferred embodiment of the invention selected for purposes of illustration is shown in the accompanying drawings, in which,

Figure 1 is a top plan view of a pin ticket,

Figure 2 is a side elevation,

Figure 3 is an enlarged side elevation of one end of a square cut staple prior to coating treatment, and

Figure 4 is a similar view after coating.

Referring to the drawings, a pin ticket 1 is illustrated in Figures 1 and 2 in which the wire staple 2 is secured to the end of the ticket in the conventional manner. According to the present invention, the ends 3 of the wire from which the staple is formed are

preferably square cut, as illustrated in Figure 3, according to methods which are well known in the art in order that the said ends may be as free as possible from burrs or other jagged projections which would tend to damage the goods or injure the fingers of the users. Preferably the said square cut is made

prior to the insertion of the staple in the ticket, although it will be understood that the wire may be cut and inserted in the ticket, and the ends of the staple may be sub-

sequently treated to provide the square cut if desired.

After the staples are cut, the ends are preferably rounded as illustrated in Figure 4. This rounding is preferably accomplished by coating the ends of the staples with suitable material. In order to form the desired rounded end, the coating operation is preferably performed by dipping the ends of the staples into the coating material while the said material is maintained in fluid condition, for it has been found that there is a tendency for the coating material to collect on the severed surface of the wire in globular form, that is, with a smoothly rounded surface 4. By suitably controlling the degree of fluidity of the coating material the size and shape of the said globule may be varied as desired.

A coating of metal, preferably tin, because of the non-corrodible properties of this metal, has been found particularly satisfactory but other metal or non-metallic material of suitable hardness may be used.

When tin is used the ends of the staples are first treated with a suitable flux and are then dipped in the molten metal, preferably several times in succession. In this manner a globule of tin is formed on the severed surface of each end of the staple which provides a substantially round surface which readily penetrates the fabrics or other material to which it may be desired to attach the tickets. The metal coating also covers any slight irregularities of the end surface of the wire, thus giving the ends of the staples a smooth surface which will not damage the goods and which will not injure the hands of the users.

In the case of metallic coating, the desired degree of fluidity of the molten metal may be obtained by suitably controlling the temperature. It has been found that good results may be obtained where tin is used as the coating metal if the metal is maintained at a temperature of approximately 570 degrees F.

It will be noted that where the coating material is non-corrodible, such as tin, the entire surface of the end of the pin is protected,

and the goods to which the tickets are attached are protected from rust stains, etc., which sometimes result with the use of ordinary staples.

5. It is to be understood that while staples having square cut ends are particularly well adapted for coating, for reasons described above, staples cut in other ways may be coated as described herein to advantages, for 10 a coating in any case covers some of the roughness incidental to cutting, and also provides a non-corrodible surface which prevents rusting.

It is also to be understood that the invention 15 may be variously modified and embodied within the scope of the subjoined claims.

I claim as my invention:

1. A pin ticket comprising a tag and wire staple secured thereto, the said wire staple 20 having a leg projecting from the tag, and having a rounded penetrating end formed of protective material of a cross-sectional area nowhere materially exceeding the cross-sectional area of the wire.
- 25 2. A pin ticket comprising a tag and wire staple secured thereto, the said wire staple having a leg projecting from the tag, and having a square cut end, the said square cut end being rounded and protected by a globule 30 of protective material of a cross-sectional area nowhere materially exceeding the cross-sectional area of the wire.
3. The method of rounding and protecting 35 the ends of pin ticket staples which comprises dipping said ends in fluid coating material, withdrawing said ends and holding them in position to permit a globule of said fluid coating material to form and harden thereon, and maintaining said fluid coating material at 40 the time of dipping said staple ends at a degree of fluidity such that the formed globule has a cross-sectional area nowhere materially exceeding the cross-sectional area of the staple.
- 45 4. The method of rounding and protecting the ends of pin ticket staples which comprises dipping said ends in molten tin, withdrawing said ends and holding them in position to permit a globule of tin to form and 50 harden thereon, and maintaining said molten tin at the time of dipping said staples at a temperature of approximately 570° F.

In testimony whereof, I have signed my name to this specification this 15th day of November, 1928.

FREDERICK W. LAENCHER.
